UNITED STATES PATENT OFFICE.

ADAM H. MEYERS, OF MELMORE, OHIO.

SLATE-DRESSING MACHINE.

SPECIFICATION forming part of Letters Patent No. 327,811, dated October 6, 1885.

Application filed July 11, 1885. Serial No. 171,359. (No model.)

To all whom it may concern:

Be it known that I, ADAM H. MEYERS, a citizen of the United States, residing at Melmore, in the county of Seneca and State of Ohio, have invented certain new and useful Improvements in Slate-Machines; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a representation of a front elevation. Fig. 2 is a vertical section on line $x-x$, Fig. 1. Fig. 3 is a horizontal section on the line $y-y$, Fig. 1. Fig. 4 is a horizontal section of the line $z-z$, Fig. 1.
20 My invention relates to machines for punching nail-holes in slate shingles, and at the same time trimming or shearing the shingles to give them the desired angles; and the invention consists in the construction and novel combination of parts, as will be hereinafter fully described, and particularly pointed out in the claims.

25 Referring by letter to the accompanying drawings, A and B designate two parallel base-sills, which are connected at their rear ends by a cross-sill, B', to give them stability.

C and D designate auxiliary sills or notched clamping-pieces, which rest upon and are bolted to the upper faces of the primary sills 30 A and B, and partially embrace the lower ends of the uprights E E' of the frame and hold them firmly in place on the base-sills. These uprights E E' are provided with elongated vertical slots G G, which extend from 35 about the middle of their heights to their upper ends. The uprights E E' are connected at their upper ends by a stringer or girder, H, having depending end pieces, H', which abut against and are secured to the outer faces of 40 the uprights E E'.
45

To the under faces of the girder H' are secured blocks I I, which abut against the inner faces of the uprights E E' and give additional strength to the structure.

50 At a proper height above the base-sills the uprights E E' are provided on their inner

faces with rearwardly-extending arms J J', which latter are provided on their inner faces, at their rear ends, with bearings J² J², for the journals J³ J³ of the treadle-arms K K. The 55 connecting-rod K', between the lower ends of the treadle-arms K, is provided with a spool or foot-piece, K², and the treadle-arms K K coil once around their journals and extend forward and upward and connect with the 60 lower ends of the vertical draw-rods L L. The draw-rods L L pass up through the slot L' in the horizontal bar M, which rests on and is secured to blocks M', which are in turn secured to the inner faces of the uprights E E', 65 so that the upper edges of the blocks M' come just below the lower ends of the elongated vertical slots G G.

Upon the horizontal stationary bar M is secured the horizontal adjustable frame N, by 70 bolts N N', passed up through the slot L', and through elongated slots N² in the parallel arms N³ N³ of the frame N, and provided with securing-nuts N⁴ N⁴, to hold said frame N to its adjustments, which are horizontal either 75 back or forth, and at right angles to the slotted stationary bar M. At their forward ends the parallel arms N³ N³ are connected by two transverse parallel arms N⁵ N⁵, having a space, N⁶, between them, through which the material punched from the slates falls. Upon these 80 two parallel arms N⁵ N⁵ are secured two adjustable anvils, O O', having their punch-holes O² O² rectangular in outline at their mouths or upper ends, and circular in outline at their lower or discharge ends.

Attached to the outer side of the anvil O' is a guide-plate, P, against which one straight edge of the sheet of slate is placed in position for clipping and punching the same.

Upon the horizontal bar M, between the arms of the horizontal adjustable frame N, are secured the lower blades, Q Q', which converge from the front toward the rear, and to the same bar, at the middle line between the 95 converging blades Q Q', is secured a hinged horizontal arm, R, having a slotted adjustable angular slide, R', secured upon its upper face, which serves as a stop for the forward end of the slate when in position to be clipped and 100 punched.

Above the stationary horizontal slotted bar

M, I provide a horizontal longitudinally-slotted sliding bar, S, which is secured to the lower end of a vertical guide-stem, S', which latter works through a bearing, S², on the girder or top rail of the supporting-frame, and is provided with a removable head, S³, held in place by a set-screw, S⁴. The stem S' is held in and returned to its normal position by a coil-spring, S⁵, interposed between the bearing S² and the removable head S³. The bar S is provided with end projections, T T, which enter the vertical slots in the uprights of the main frame and guide the sliding bar S in its vertical movements.

15 On its under face the slotted sliding bar S is provided with the upper pair of converging blades or shearing-knives, U U, which are provided on their backs or upper edges with threaded studs U' U', which pass up through the slot S⁶ in the slotted sliding bar S and are secured in place by nuts S' S'.

Upon the upper face of the slotted sliding bar S are secured the slotted adjustable arms V V, which are held in place thereon by bolts 25 V' V' and nuts V² V². At their forward ends these adjustable arms V V are provided with the vertically-depend ing punches V³ V³, which are cylindrical in cross-section, tapering from above downward, and are pointed at their lower ends, and are located directly above the anvils O O', so that when the punches V³ V³ are caused to descend, by using the treadle 30 they will pass through the slate, when in place, and enter the punch-holes O² O² and drive the material to be punched out through the punch-holes O² O². At the same time that this operation is being performed the upper pair of shearing knives or blades will descend with the slotted sliding beam, and the sheet of slate 35 resting on the lower pair of blades will be cut or sheared between the two sets of knives to present the desired angles at one end upon the sides of the slate. As soon as the pressure is removed from the treadle, the coil-spring, which 40 has been compressed, will expand and raise the slotted sliding bar M, and with it the upper pair of blades or shearing-knives.

Having thus fully described my invention, what I claim as new, and desire to secure by 50 Letters Patent of the United States, is—

1. In a slate-dressing machine, the combination of the main frame having the vertically-slotted standards, the longitudinally-slotted transverse bar M, the shearing-knives, and

hinged bar carrying the adjustable stop arranged thereon, the horizontally-adjustable frame N, carrying the laterally-adjustable anvils, the upper vertically-moving bar carrying the punches and shearing-knives, and the draw-rods connecting the said bar with the treadle, substantially as specified.

2. In a machine for trimming and punching slate, the horizontally-adjustable frame carrying the laterally-adjustable anvils and trimming-knife, and adapted to serve with a main frame having a slotted beam, as M, substantially as specified.

3. The combination, with the main frame having the vertically-slotted standards and the rearwardly-extending arms J J, of the longitudinally-slotted bar S, moving in the slots of the standards and carrying the adjustable shearing blades and punches, the treadle, and draw-rods connecting the treadle with the said moving bar, substantially as specified.

4. The combination, with the main frame, of the stem S', passing through an aperture in the top bar thereof and surrounded by a spiral spring, the vertically-moving bar S, secured to the lower end of the said stem, the cutting device, the treadle, and draw-rods connecting the treadle with the vertically-moving bar, substantially as specified.

5. The combination, with the main frame having the vertically-slotted uprights and the slotted stationary lower horizontal bar, the hinged stop, and the adjustable covering, knives arranged on the said bar, the longitudinally-slotted vertical slide-bar, its adjustable punch-arms, with punches, of the vertically-arranged spring-actuated guide-stem passing down through the top beam of the main frame, and draw-rods connecting the hinged treadle with the vertically-moving slotted bar, substantially as specified.

6. The combination, with the longitudinally-slotted transverse stationary bar M, provided with the rear hinged adjustable stop, R, of the horizontally-adjustable frame provided with the adjustable anvils, substantially as specified.

In testimony whereof I affix my signature in presence of two witnesses.

ADAM H. MEYERS.
